UNITED STATES PATENT OFFICE.

BERT M. KENT, OF WASHINGTON, DISTRICT OF COLUMBIA, ASSIGNOR, BY DIRECT AND MESNE ASSIGNMENTS, TO THE KENT VACUUM CLEANER COMPANY, INC., OF ROME, NEW YORK, A CORPORATION OF NEW YORK.

VACUUM-CREATING AND DUST-SEPARATING MACHINE.

1,220,641.

Specification of Letters Patent.

Patented Mar. 27, 1917.

Application filed August 26, 1913. Serial No. 786,749.

To all whom it may concern:

Be it known that I, BERT M. KENT, residing at Washington, District of Columbia, have invented certain new and useful Improvements in Vacuum-Creating and Dust-Separating Machines, of which the following is a specification.

This invention has for one of its objects the provision of a machine for creating vacuum and separating dust and dirt from air, which will be especially adapted for use in connection with vacuum cleaning systems.

Another object is to provide a machine of this class which is adapted for permanent installation in a building and in combination with suitable suction pipes which lead to convenient points throughout the building where a cleaning hose may be attached.

A further object is to provide a machine of this class which is power operated and the operating parts of which are fully inclosed and supported on the base of the machine whereby vibration and noise due to the operation of the machine will be reduced to a minimum.

A further object is to provide a machine of this class in which the "cyclone" principle of dust separation is employed and the use of screens avoided.

A further object is to provide a unitary machine of neat and symmetrical appearance which will be simple in construction, efficient, and the moving parts of which will be readily accessible, although fully inclosed.

A further object is to provide a machine of this class in which the dust and dirt will be collected in a receptacle which can be readily removed from time to time for the purpose of emptying same.

The invention may be embodied in different forms of machines and I have illustrated in the accompanying drawings one form which accomplishes all of the above objects. In the drawings:

Figure 1 is a central vertical section of the machine.

Fig. 2 is a section on line 2—2 of Fig. 1; and

Fig. 3 is a section on line 3—3 of Fig. 1, the fan being shown in plan view.

Referring to the drawings, it will be seen that the machine illustrated is of the vertical

type and comprises a base 10 which supports a motor 11 having an upward shaft extension 12. On the shaft extension 12 is mounted a centrifugal fan 13 which is inclosed in a casing comprising upper and lower sections 14 and 15, these sections being secured together by bolts 16 and coöperating to form an outlet pipe 17 having a flange 18 to which a flanged sleeve 19, for the exhaust pipe 20, may be secured.

The lower section 15 of the fan casing is supported on the base 10 by means of legs 21, these legs being secured to the base and casing by bolts 22 and 23, respectively. The lower section of the casing has a central opening 24, for the shaft extension 12, this opening being of such size that the casing will be out of contact with the rotating parts so that any vibrations in the rotating parts will not be transmitted directly to the casing.

The fan 13 may be of any suitable construction and in the form illustrated consists of a hub 25, to which are secured a lower disk 26 and blades 27. The blades 27 are arranged between the disk 26 and an upper disk 28 and are secured to both disks. Arranged between the blades 27 and also secured to the disks 26 and 28 are other blades 29 which are not connected with the hub 25. The upper disk is provided with a central inlet opening 30 through which the air enters, the air being discharged at the periphery of the fan into a diffuser which consists of two rings 31 and 32 between which are guide vanes 33 for so guiding the air, discharged from the fan, that its velocity or kinetic energy will be largely converted into potential or pressure energy. The rings 31 and 32 engage suitable grooves or seats in the sections of the fan casing and are preferably unattached to either section so that the sections may be readily separated. When the upper section of the casing is taken off the diffuser may be readily lifted from the lower section and thus removed. The air is discharged by the diffuser into the annular passage formed in the fan casing and thence passes out through the exhaust pipe 20.

The space between the base 10 and the lower section of the fan casing is inclosed by a cylindrical casing 34 which may be

provided with a hand hole permitting access to the motor. For the purpose of ventilating the motor the casing 34 is provided with upper and lower rows of openings 5 35 and 36, respectively.

Secured to the upper section 14 of the fan casing is a cylindrical shell or casing 38, the shell having riveted or otherwise attached thereto an inwardly turned flange 39 which is secured to the fan casing by screws 40. A flange 41 on the fan casing surrounds the lower end of the shell 38 and the joint between these parts is suitably sealed to prevent air leakage. At the upper 15 end of the shell 38, a ring 42 is provided, this ring having a groove for a packing 43 which is engaged by a removable cover 44. The ring 42 is also provided with lugs 45 to which clamping bolts 46 for the cover 20 are pivoted. The cover has ears 47 which are slotted to receive the bolts 46 and which are engaged on their upper side by the nuts 48.

Tangentially arranged on the upper part 25 of the shell 38 is an inlet fitting 49 having a flange 50 to which a flange sleeve 51 is bolted. The sleeve 51 has the suction pipe 52 attached thereto. Another inlet fitting 53 is secured to the shell 38, preferably on 30 the same level as fitting 49. The end of fitting 53 is normally closed by a suitable plug 54 which may be removed to permit the attachment of a flexible hose for cleaning the room in which the machine is located. From Fig. 2 it will be apparent that 35 the air entering through the fittings 49 and 53 will whirl in the same direction within the shell 38 and for reasons which will be explained more fully hereinafter the direction of movement of the air within the shell 40 is the same as the rotation of the fan.

The upper section 14 of the fan casing is provided with a central opening 55, which registers with the fan inlet 30, and this 45 opening is surrounded by an upwardly projecting flange 56 to which a vertical pipe 57 is attached, this pipe preferably extending to a point adjacent the cover 44 and having its upper end surrounded by a hood or 50 baffle 58 carried by the cover 44.

Arranged within the shell 38 and resting on the fan casing is an annular dirt collecting pan 59. This pan is provided with handles 60 and has its outer wall flanged outwardly at the top to loosely fit an apron 61 on the shell 38. At its center the pan 59 has a tube 62 secured to the bottom thereof and adapted to surround the pipe 57, the upper end being flanged inwardly to more 60 closely fit the pipe 57.

In the operation of the machine the air which enters the inlets 49 and 53 whirls around on the interior of the shell 38 and the dirt and dust are thrown out against the 65 shell by centrifugal force and fall into the

pan 59, the apron 61 deflecting the dirt so as to largely prevent it from falling between the shell and the pan and also permitting the pan to be materially smaller than the shell so that the pan can be easily removed. By having the inlets below the top of pipe 57 it is practically impossible for any particles of appreciable size to get into the pipe and be carried through the machine, but as a further protection I have 70 provided the hood 58. The air moves in a spiral path from the inlets to the pipe 57 and then spirally down through the pipe to the fan inlet 30. In order to reduce the power losses in the fan to a minimum it is 75 desirable to have the air and the portion of the fan blade which it strikes on entering the fan move in substantially the same direction and at as nearly the same velocity as practicable. This has been accomplished 80 heretofore by curving the inner ends, and by providing guide vanes which will direct the air into the fan with a minimum amount of shock. By giving the air a whirling or 85 spiral motion, as I have done, it is possible 90 to minimize the shock, and at the same time provide a simple fan construction in which the blades are radial.

As will be seen from the drawings, the machine is fully inclosed so that none of the 95 working parts are exposed. It is possible, however, to readily gain access to the working parts by taking out the bolts 16 and removing the upper half of the fan casing, together with the parts carried thereby. This 100 exposes the fan and the diffuser, and, if necessary, these may be readily removed and then the lower half of the fan casing taken off to expose the motor. The casing 105 inclosing the motor chamber may be also readily removed.

By providing the openings in the casing from the motor chamber, the air which is heated by the motor will pass out through the upper openings and cooler air will be 110 drawn in through the lower openings, a circulation being thus maintained which will effectually cool the motor.

Having thus described my invention, what is claimed is:

1. In a vacuum creating and dust separating machine, the combination of a dust collecting chamber of circular form having a vertical axis and a horizontal tangentially arranged inlet opening whereby the air is 120 given a cyclonic motion within the chamber, and a centrifugal fan rotating in the same direction as the air in said chamber and communicating with the chamber above the level of said inlet.

2. In a vacuum creating and dust separating machine, the combination of a dust collecting chamber of circular form having a vertical axis and a horizontal tangentially arranged inlet whereby the air is given a cy- 130

clonic motion within the chamber, a centrifugal fan rotating in the same direction as the air in said chamber, and means communicating with said chamber above the 5 level of said inlet for conducting air from the chamber to said fan and arranged to maintain the cyclonic motion of the air until it reaches the fan.

3. In a vacuum creating and dust separating machine, the combination of a dust collecting chamber of circular form having a vertical axis and a horizontal tangentially arranged inlet opening whereby the air is given a cyclonic motion within the chamber, 10 a centrifugal fan rotating in the same direction as the air in said chamber and arranged at the bottom thereof, and a conduit opening into the upper part of said chamber above said inlet and having its lower end in communication with the inlet opening to said fan.

4. In a vacuum creating and dust separating machine, the combination of a dust collecting chamber of circular form having a vertical axis and a horizontal tangentially arranged inlet opening whereby the air is given a cyclonic motion within the chamber, a centrifugal fan rotating in the same direction as the air in said chamber, and there 25 being an unscreened passage for the air from a point in said chamber above the level of said inlet to the fan whereby the cyclonic motion of the air is maintained and the air is permitted to enter the fan tangentially.

30 5. In a vacuum creating and dust separating machine, the combination of a vertical cylindrical dust separating chamber having a tangentially arranged inlet at an intermediate point in the side wall thereof, a removable cover for the top of said chamber, a pan in the lower part of the chamber adapted to receive the dust and vertically removable through the top of the chamber, vacuum creating means below said chamber, and 35 a pipe extending upwardly in the center of said chamber to a point near the top thereof.

6. In a vacuum creating and dust separating machine, the combination of a vertical cylindrical dust separating chamber, 50 a vacuum creating means below said chamber, a pipe communicating with the inlet to said means and extending upwardly in the center of said chamber, a suction pipe having communication with said chamber 55 through the side wall thereof below the upper end of said first-mentioned pipe, and a removable dust collecting pan surrounding said first-mentioned pipe and arranged wholly below the suction pipe inlet. 60

7. In a vacuum creating and dust separating machine, the combination of a vertical cylindrical dust separating chamber, vacuum creating means having an inlet communicating with said chamber through the 65 bottom wall thereof, a central vertical pipe secured to the bottom wall of the chamber and in communication with said inlet, a removable top for said chamber, and a removable annular dust collecting pan in said 70 chamber surrounding said pipe, said chamber having a tangential suction pipe connection on the side wall thereof above said pan.

8. In a vacuum creating and dust separating machine, the combination of a vertical cylindrical dust separating chamber, 75 vacuum creating means having an inlet communicating with said chamber through the bottom wall thereof, a central vertical pipe secured to the bottom wall of said chamber 80 and in communication with said inlet, a removable top for said chamber, a cylindrical baffle secured to said top and concentric with and extending to a point below the top of said pipe, a removable annular dust collecting pan surrounding said pipe, and a suction pipe connection on the side wall of the chamber above said pan. 85

In testimony whereof I affix my signature in presence of two witnesses.

BERT M. KENT.
